UNITED STATES PATENT OFFICE.

FREDRICK S. BRAGG, OF CORNING, NEW YORK.

SPARK-ARRESTER.

SPECIFICATION forming part of Letters Patent No. 325,907, dated September 8, 1885.

Application filed June 3, 1885. (No model.)

To all whom it may concern:

Be it known that I, FREDRICK S. BRAGG, of Corning, in the county of Steuben, in the State of New York, have invented new and useful Improvements in Spark-Arresters, of which the following, taken in connection with the accompanying drawings, is a full, clear, and exact description.

The objects of this invention are, first, to prevent accumulation of cinders in the smoke-box; secondly, to discharge the cinders from the bottom of the smoke-box immediately after they emerge from the flue; thirdly, to extinguish the fire in the cinders before discharging them from the smoke-box; and, fourthly, to moderate the draft through the flues and stack so as to prevent the fine particles of fuel from being drawn out of the fire-box and expelled through the stack, and thus economize in the consumption of fuel; and to the attainment of these objects my invention consists in the novel construction and combination of parts, as hereinafter fully described, and specifically set forth in the claims.

In the accompanying drawings, Figure I is a longitudinal section of the smoke-box of a locomotive-boiler provided with my improvements. Fig. II is a vertical transverse section on line *x* *x*, Fig. I, on a reduced scale; and Fig. III is an enlarged detached plan view of the under side of the gates or valves which are applied to the opening in the bottom of the smoke-box.

Similar letters of reference indicate corresponding parts.

E represents the forward end of a locomotive-boiler; *C*, the flue-sheet at said end; *h h*, the flues; *D*, the smoke-box, and *A* the stack.

B denotes the wire-netting extended horizontally across the smoke-box, so as to be interposed between the ends of the flues *h h* and stack *A*, and thus arrest the escape of the cinders and sparks through the stack.

O represents an opening in the bottom of the smoke-box at the end farthest from the flue-sheet *C*, the latter location of the said opening being preferred, for the reason hereinafter explained. A frame, *a*, secured to the under side of the smoke-box and surrounding the opening *O*, is provided with a suitable valve

or gate, *b*, which in this case is represented in the form of a plate sliding in grooves in opposite sides of the frame *a*.

Although my invention is designed to obviate accumulation of cinders in the smoke-box, yet in case the constant outlet herein-after described becomes clogged, by reason of the cinders being moistened, the gate *b* can be opened to permit of removing the cinders.

A spout, *e*, extending from the frame *a* downward and rearward, serves to deliver the cinders onto the road-bed in the center of the track.

The valve or gate *b*, I provide with a port or opening, *c*, for the inlet of air and for the constant discharge of cinders.

A supplemental valve, *d*, is pivoted on the gate *b* in such a position that while permitting of regulating the size of the opening it is prevented from entirely closing the same, and thus leaves a permanent opening. Said supplemental valve is connected by a rod, *r*, with a lever, *l*, which may be arranged either at the front end of the smoke-box, as shown, or in the cab of the engine, as may be desired. By means of said lever the supplemental valve can be adjusted in its position at will of the engineer.

The operation of my invention is as follows: When the engine is in operation, and especially when, with high pressure of steam and full stroke of valve, the vacuum produced in the smoke-box by the expulsion of the exhaust-steam through the stack is to a certain degree supplied with air through the port or opening *c*, and thus the draft through the flues is moderated so as to prevent fine particles of fuel from being drawn through the flues, and consequently the consumption of fuel is economized. By locating the opening *c* at the end farthest from the flue-sheet *C*, as hereinbefore stated, the current of the incoming air is caused to meet the current of products of combustion under the wire netting *B*, and while the fine dust escapes through the netting and escapes with the smoke through the stack, the meeting of the cold current of air with the cinders checks the progress of the latter, and more or less extinguishes the sparks. The aforesaid counter-currents produce a whirl of the cinders which gradually carries the cinders to the

opening *c*, and on arrival thereat they drop by gravity through said opening, as indicated in Fig. I of the drawings, thus preventing accumulation of cinders in the smoke-box; and inasmuch as the discharge of cinders is constant, and consequently in a comparatively small stream, to the road-bed, the scattering of cinders over the working parts and bearings of the engine, and the resultant injuries to the same, are to a great extent obviated.

The aforesaid constant discharge of cinders from the smoke-box is an indisputable fact proven to me by practical tests made by me. After running the engine all day with coal as fuel I have found the smoke-box nearly empty, there being usually a very small quantity of cinders left on the bottom of the smoke-box, between the flue-sheet and opening *o*.

Having described my invention, what I claim as new, and desire to secure by Letters Patent, is—

1. The combination, with the smoke-box of a locomotive-boiler, of a cinder-discharge opening in the bottom of said smoke-box at the end farthest from the flue-sheet, a valve or gate across said opening and limited to leave a permanent opening, substantially as and for the purpose set forth.

2. The combination, with the smoke-box of a locomotive-boiler, of a cinder-discharge opening in the bottom of said smoke-box at the end farthest from the flue-sheet, a gate across said opening and provided with an air-inlet port through it, and a supplemental valve or gate for regulating said inlet, substantially as described and shown, for the purpose set forth.

3. The combination with the smoke-box of a locomotive-boiler, of a wire-netting interposed between the ends of the flues and stack, a cinder-discharge opening in the bottom of said smoke-box at the end farthest from the flue-sheet, a gate across said opening and provided with an air-inlet port through it, and a supplemental valve or gate for regulating said inlet, substantially as described and shown, for the purpose set forth.

In testimony whereof I have hereunto signed my name and affixed my seal, in the presence of two attesting witnesses, at Corning, in the county of Steuben, in the State of New York, this 22d day of May, 1885.

FREDRICK S. BRAGG. [L. S.]
